(57) **CLAIM**

The ornamental design for a compostable container as shown and described.

DESCRIPTION

FIG. 1 is a perspective view of a compostable container, showing my new design;

FIG. 2 is a front view thereof, the back view being the same;

FIG. 3 is a right side view thereof, the left side view being the same;

FIG. 4 is a top view thereof;

FIG. 5 is a bottom view thereof; and,

FIG. 6 is an exploded perspective view thereof.

The back view of the embodiment of a compostable container and lid is identical to the front view of FIG. 2 and a back view is not included separately.

1 Claim, 5 Drawing Sheets
